UNITED STATES PATENT OFFICE.

HURLEY D. RALSTON, OF CHICAGO, ILLINOIS.

ELECTRIC SEALING DEVICE.

Application filed April 2, 1926. Serial No. 99,385.

This invention relates to certain novel improvements in electric sealing devices and more particularly to a device of this character for melting and applying wax to an envelope or like article for sealing the closure flaps thereof and has for its principal object the provision of an improved construction of this character which will be highly efficient in use and economical in manufacture.

Among the several objects of the invention is the production of a device of this character wherein there is provided a simple combination and arrangement of parts for measuring, melting and supplying powdered wax to be melted and applied to an article to be sealed.

Other objects will appear hereinafter.

The invention consists in the combination and arrangement of parts hereinafter described and claimed.

The invention will be best understood by reference to the accompanying drawing illustrating the preferred form of construction, and in which—

Figs. 1 and 2 are vertical sectional detail views of the invention illustrating the preferred form of construction,

Fig. 3 is a sectional detail view of the same taken substantially on line 3—3 of Fig. 2,

Fig. 4 is a fragmentary sectional detail view of the same taken substantially on line 4—4 of Fig. 1, and

Fig. 5 is a sectional detail view of the same taken substantially on line 5—5 of Fig. 1.

Referring more particularly to the drawing, illustrating the preferred form of construction, a barrel is indicated at 10 and includes cylindrical side walls 11 and a bottom wall 12 having an opening 13 formed centrally therein. The upper end portion of the barrel is closed by a cap 14 having a central opening 15 formed therein and including depending flanges 16 adapted for frictional engagement with adjacent interior portions of the cylindrical walls 11.

Arranged in the barrel 10 at the lower end portion thereof, as illustrated in Figs. 1 and 2, is a tubular member 17 defining at its upper end portion a melting chamber 18. The walls of this melting chamber are spherically shaped to define an entrance 19

at its upper end portion. Below this melting chamber 18 the tubular member defines a receiving chamber 20 opening, at its lower end portion, into a sealing chamber 21 where the melted wax, indicated at 22, is received for application to an article to be sealed.

The walls of this receiving chamber 20 are likewise spherical in shape and define a restricted passage 23 opening communication between itself and the melting chamber 18. The lower end portion of the tubular member is cylindrically shaped to define the sealing chamber 21 herein mentioned.

This tubular member 17 is preferably formed of heat conducting material so that the melted wax will be retained in melted condition until the same is applied to the article to be sealed, in a manner hereinafter set forth.

Arranged between the interior wall surfaces 24 of the barrel and the outer wall surfaces 25 of the walls defining the melting chamber is a heating unit generally indicated at A. This heating unit includes an asbestos base 26 receiving a heating coil 27 which is connected in circuit with terminal posts 28 through the medium of conductor wires 29. This heating coil is disposed to surround the outer wall portions 25 and in contact therewith so that the heat generating from these heating coils will be conducted by the tubular member to melt the powdered wax received by the melting chamber and so that wax thus melted will remain in melted condition until applied to the article to be sealed.

Arranged in the barrel 10 above the tubular member 17 is a second tubular member 30. This tubular member is preferably formed of non-heat conducting material and has its lower end portion shaped to define a spherical measuring chamber 31. This portion of the tubular member 30 defines a restricted passage 31' which opens communication between this measuring chamber and the upper end portion 32 of the tubular member 30. This upper end portion 32 of the tubular member 30 defines a funnel shaped mouth 33 including inwardly and downwardly tapered wall portions 34. These tapered wall portions 34 serve to guide the powdered wax 35 into the measuring chamber 31 under certain conditions.

As illustrated in Figs. 2 and 5 a door 36

is included as a part of the cylindrical walls 11 for the purpose of permitting replenishing of the powdered wax to the storage chamber 35 defined by the upper end portion of the barrel 10.

As will be noted in Figs. 1 and 2 the sealing chamber 21 is in registration with the opening 13 to permit the expulsion of the melted wax applied to an article to be sealed 19 in a manner to be hereinafter set forth.

The mechanism for applying the melted wax to an article to be sealed includes a plunger 38 mounted for movement longitudinally of the barrel 10. The upper end portion of this plunger includes a reduced end portion 39 threaded to receive a button 40. This plunger 38 works through the central opening 15 formed in the cap 14 and includes a reduced portion 41 which is adapted, when the plunger is in the position illustrated in Fig. 2, to open communication between the storage chamber 35 and the measuring chamber 31. The passage 31' affording such communication is normally closed by an enlarged portion 42 of the plunger when the plunger is in the position illustrated in Fig. 1. Below this reduced portion 41 is a second reduced portion 43 which is adapted to permit communication between the measuring chamber 31 and the melting chamber 18 when the plunger is in the position illustrated in Fig. 1 with the portion 42 thereof closing passage through the restricted passage 31'. This portion 42 of the plunger is likewise adapted to close passage through the restricted passage 19 when the plunger is in the position illustrated in Fig. 2. When the plunger is in the position illustrated in Fig. 1 the enlarged lower end portion 44 thereof closes passage between the melting chamber 18 and the receiving chamber 20. This enlarged portion 44 is substantially conical in shape and is of such diameter so as to snugly pass into the sealing chamber 21 when the plunger is manually depressed into its lowermost position beyond that illustrated in Fig. 2.

This conical shaped end portion 44 of the plunger has a central threaded bore 45 formed therein to receive the threaded stud 46 formed as an integral part of a seal 47.

To momentarily stop depressing of the plunger 38, for reasons hereinafter set forth, 55 I provide opposite detents 48 slidably supported by bearing brackets 49 carried by the cap 14 and normally urged in engaged position with adjacent portions of the plunger by spring members 50. These detents 48 are adapted to engage in an annular recess 51 formed in the upper end portion of the plunger, when the plunger is in the position illustrated in Fig. 2. It will be noted that when the plunger is in this 65 position communication is opened between

the melting chamber 18 and the receiving chamber 20 and between the receiving chamber 20 and the sealing chamber 21. This permits a certain amount of the melted wax to find entrance into the sealing chamber 21 70 where upon further depressing of the plunger the seal 47 thereof will be brought down upon the melted wax received by this sealing chamber. To permit the required amount of melted wax to find confinement in 75 this sealing chamber the plunger is momentarily resisted from downward movement by the detents 48 when in engagement in the annular recess 51.

The plunger is normally held in its extreme upper position, with the portion 42 closing the restricted passage 31' and with the conical shaped end portion 44 closing communication through the restricted passage 23, by a spring member 52. This spring 85 member 52 is mounted between the button 40 and the cap 14 in embracing position with respect to adjacent portions of the plunger as best illustrated in Fig. 1.

When the device is inoperative the plunger 90 is normally disposed to close communication between the restricted passages 23 and 31'. In this position it will be noted that communication is permitted through the restricted passage 19 to permit a predetermined amount of powdered wax confined in the measuring chamber 31 to find confinement in the melting chamber 18 where the powdered wax is melted into condition to be applied to the article to be sealed. Upon 100 operation of the device the plunger is disposed to close communication through the restricted passage 19 and to open communication through the restricted passages 23 and 31'. In this position of the plunger, a predetermined amount of the powdered wax 105 35 is permitted to find confinement into the measuring chamber 31 and the melted wax in the melting chamber 18 is permitted to pass into the receiving chamber 20 and from 110 there into the sealing chamber 21. Upon further depressing of the plunger 38 the seal 47 is brought down upon the melted wax confined in the sealing chamber to press the wax therein into adhesive relation with the 115 article to be sealed.

When the plunger is manipulated to move into its lowermost position to bring the seal 47 down upon the melted wax in the sealing chamber 21 it is manifest that by reason of a 120 manually imposed force upon the plunger to move it in the direction to bring the seal 47 into such a position that the action of the springs 50 permitting further movement of the plunger, pass the point of engagement 125 between the detents and the annular recess. These detents serve in their principal capacity, as herein mentioned, to momentarily stop movement of the plunger in the direction to bring the seal upon the melted wax. During 130

this momentary stopping of the plunger the melted wax is permitted to find confinement in the sealing chamber 21.

While I have illustrated and described the 5 preferred form of construction for carrying my invention into effect, this is capable of variation and modification without departing from the spirit of the invention. I, therefore, do not wish to be limited to the 10 precise details of construction set forth, but desire to avail myself of such variations and modifications as come within the scope of the appended claims.

Having described my invention, what I 15 claim as new and desire to secure by Letters Patent is:

1. A sealing device including a tubular member defining a melting chamber and a receiving chamber and a restricted passage 20 opening communication between the melting chamber and the receiving chamber, there being a sealing chamber defined by the tubular member in communication with the receiving chamber opposite the restricted passage, a movable member movable longitudinally through the tubular member and including an enlarged end portion adapted to obstruct passage through the restricted passage and adapted to open communication 25 through the restricted passage when the movable member is moved in a direction to dispose the enlarged end portion in the sealing chamber, and a seal carried by said enlarged end portion of the movable member.

2. A sealing device including a tubular member defining a melting chamber and a receiving chamber and a restricted passage opening communication between the melting chamber and the receiving chamber, there 30 being a sealing chamber defined by the tubular member in communication with the receiving chamber opposite the restricted passage, a movable member movable longitudinally through the tubular member and including an enlarged end portion adapted to obstruct passage through the restricted passage and adapted to open communication 35 through the restricted passage when the movable member is moved in a direction to dispose the enlarged end portion in the sealing chamber, a seal carried by said enlarged end portion of the movable member, and means adapted to momentarily obstruct movement of the movable member when the movable member is moved to dispose the enlarged end portion from obstructing position in the restricted passage.

3. A sealing device of the class described including a tubular member defining a plurality of chambers and restricted passages opening communication between the chambers, and a movable member having portions disposed to obstruct passage through certain of the restricted passages and including reduced portions adapted to open communica-

tion between said certain of the passages when the said portions of the movable member are disposed to obstruct passage through the other of the passages, in combination with a seal carried by the movable member 70 adapted to operate upon matter discharged from one of said chambers.

4. A sealing device including a barrel defining at its upper end portion a storage compartment and at its lower end portion a discharge opening, a member confined in the barrel defining a measuring chamber adapted under certain conditions to have communication with the storage chamber and a melting chamber adapted under certain 75 conditions to have communication with the measuring chamber, a member movable longitudinally in the barrel and including a portion adapted to alternately close communication between the measuring chamber and the storage chamber and between the measuring chamber and the melting chamber, there being an enlarged portion at an end of the movable member adapted to close the discharge passage of the melting chamber when the portion of the movable member is disposed to close communication between the measuring chamber and the storage chamber, and a seal carried by the enlarged end portion of the movable member adapted to operate upon 80 matter passing through the discharge passage of the melting chamber through the said opening when the enlarged end portion of the movable member is disposed in a position 85 from obstructing passage through the discharge passage and when the said portion is disposed to obstruct communication between the melting chamber and the measuring chamber.

5. A sealing device including a barrel defining at its upper end portion a storage compartment and at its lower end portion a discharge opening, a member confined in the barrel defining a measuring chamber adapted under certain conditions to have communication with the storage chamber and a melting chamber adapted under certain conditions to have communication with the measuring chamber, a member movable longitudinally in the barrel and including a portion adapted to alternately close communication between the measuring chamber and the storage chamber and between the measuring chamber and the melting chamber, there being an enlarged portion at an end of the movable member adapted to close the discharge passage of the melting chamber when the portion of the movable member is disposed to close communication between the measuring and the storage chamber, a seal carried by the enlarged end portion of the movable member adapted to operate upon substance passing through the discharge passage of the melting chamber through the said opening when the enlarged end portion 100 105 110 115 120 125 130

of the movable member is disposed in a position from obstructing passage through the discharge passage and when the said portion is disposed to obstruct communication 5 between the melting chamber and the measuring chamber, and means for normally retaining the movable member in a position with a portion thereof disposed in position to obstruct communication between the measuring chamber and the storage chamber and with the enlarged end portion disposed to obstruct passage through the discharge passage.

6. A sealing device of the class described 15 including a body defining a storage chamber, a measuring chamber in communication with the storage chamber, a melting chamber in communication with the measuring chamber and a receiving chamber in communication 20 with the melting chamber, a movable member associated with the body for closing and opening communication between the chambers defined by the body, and a seal carried by the movable member adapted to operate 25 upon matter received by the receiving chamber from the melting chamber.

7. A sealing device of the class described including a body defining a storage chamber, a measuring chamber in communication 30 with the storage chamber, a melting chamber in communication with the measuring chamber, and a receiving chamber in communication with the melting chamber, a movable member associated with the body for closing 35 and opening communication between the chambers defined by the body, and a seal carried by the movable member adapted to operate upon matter received by the receiving chamber from the melting chamber, and a heating unit surrounding the 40 walls of the melting chamber for melting matter received by the melting chamber from the measuring chamber.

8. A sealing device of the class described including a body defining a melting chamber 45 and a receiving chamber in communication with the melting chamber and a sealing chamber in communication with the melting chamber, a movable member having an enlarged end portion adapted under certain 50 conditions to close communication between the melting chamber and the receiving chamber, a seal carried by the movable member adapted to operate upon matter received by the sealing chamber to expel the matter received from said sealing chamber upon an article to be sealed by said matter, and means 55 for momentarily retarding movement of the movable member to bring the seal into operation upon the matter received in the sealing chamber.

9. A sealing device of the class described including a body defining a melting chamber and a receiving chamber in communication with the melting chamber and a sealing 65 chamber in communication with the melting chamber, a movable member having an enlarged end portion adapted under certain conditions to close communication between the melting chamber and the receiving chamber, 70 a seal carried by the movable member adapted to operate upon matter received by the sealing chamber to expel the matter received from said sealing chamber upon an article to be sealed by said matter, and means 75 for momentarily retarding movement of the movable member to bring the seal into operation upon the matter received in the sealing chamber, said means including detents carried by the body and adapted for engagement with an annular recess formed in the movable member and spring members adapted to urge the detents into engagement with the recess.

In testimony whereof I affix my signature.
HURLEY D. RALSTON.
